AMUSEMENT APPARATUS

Norman Bartlett, Weehawken, N. J.

Application December 17, 1937, Serial No. 180,413

15 Claims. (Cl. 272—17)

This invention relates to certain new and useful improvements in public amusement apparatus.

It has for its chief object to provide an apparatus of this character which is designed to produce illusory effects of movement in linear or circular paths.

Another object of the invention is to provide an illusion of movement apparatus for amusement parks and the like which employs a substantially cylindrical or drum-like enclosure having a succession of light-emitting elements applied to its interior wall and adapted to be controlled in relatively predetermined sequence to effectively produce illusory movements of the patrons relative to the enclosure as well as movement of the latter relative to the patrons.

A further object is the provision of an amusement apparatus of this character having an arrangement of mirrors therein to increase to the patron the visual size of the enclosure with a corresponding increase of illusion effect.

A still further object is to provide the apparatus with means for imparting movement to the patrons as they pass through the same and thereby accentuate the illusion of movement.

Another object is to provide a transparent mirror arrangement so disposed that spectators will see in a multiplied form the illusion effects for ballyhoo purposes.

Other features of the invention reside in the construction and arrangement of parts herein-after described and particularly pointed out in the appended claims.

In the accompanying drawings:

Figure 1 is a top plan view of the amusement apparatus embodying my invention. Figures 2 and 3 are enlarged cross sections taken on the correspondingly-numbered lines in Figure 1. Figure 4 is a fragmentary diagrammatic view of the means for controlling the successive group or sequence lighting of the light-emitting elements. Figure 5 is a detail side elevation of one of the upright enclosures. Figure 6 is a horizontal section of a modification form of the invention. Figure 7 is a fragmentary side elevation of the right hand or exit end thereof. Figure 8 is a cross section taken on line 8—8, Figure 6.

Similar characters of reference indicate corresponding parts through the several views.

In its general organization my amusement apparatus consists of a plurality of enclosures through which the amusement patrons may pass, such enclosures being, by preference, substantially cylindrical in shape with certain enclosures

disposed substantially horizontal and others disposed in a substantially upright position with intercommunicating walk-ways connecting the several enclosures; and light-emitting elements applied in rows or in succession to the interior walls of the enclosures with the elements in certain enclosures extending lengthwise thereof and the elements of the other enclosures extending annularly about the same, together with means for successively controlling the lighting of the light-emitting elements in predetermined group-like sequence to give the patrons different illusory movement effects of the enclosures.

By way of example, in the embodiment of the invention shown in Figure 1, the amusement apparatus consists of a pair of substantially horizontally disposed enclosures 10 and 11 which may be in the form of a drum or cylinder, and a pair of similar enclosures 12, 13 which are disposed in a substantially upright position. These pairs of enclosures may be disposed side by side or in any other appropriate manner and the enclosures 10, 11 have walk-ways or platforms 14 which extend lengthwise thereof and are located adjacent the bottom of the enclosures, the latter being open at their ends for the ingress and egress of the patrons to and from the enclosures. The upright enclosures 12, 13 have walk-ways or platforms 15 at their lower ends which are more or less U-shape in plan with the ingress and egress openings for the patrons formed at one side and in the lower portion of the enclosures, as indicated at 16 in Figures 1 and 5. The pairs of enclosures 10, 11 and 12, 13 are preferably interconnected by suitable walk-ways 17, whereby the patrons may pass from the enclosure 10 to the enclosure 12, then across a walk-way 18 through the enclosure 13 and from the latter over the adjoining walk-way 17 to the companion enclosure 11. The main entrance to the amusement apparatus is indicated at 19 and is connected by a walk-way 20 to the enclosure 10, while the exit of the apparatus is indicated at 21 and is connected by a walk-way 22 with the enclosure 11.

Disposed within each of the enclosures are light-emitting elements which are arranged in rows or in succession about the interior wall of the enclosure, and which elements are adapted to be successively lighted or flashed "on" and "off" in predetermined or group sequence to create an illusory effect of movement of the enclosure as the patrons pass therethrough. While any suitable and well known form of light-emitting elements may be provided, such as electric lamps arranged in coves about the enclo-

sures, I prefer to use neon tubes, which are indicated at 23. In the enclosures 10 and 13, these light tubes may be arranged to extend lengthwise of the enclosure substantially from end to end thereof, while in the enclosures 11 and 12 the tubes may extend annularly or in ring-like fashion about the interior walls of the enclosures, whereby different illusionary effects of movement of the enclosures are created. The longitudinal-
 10 ly-extending light-emitting elements, when flashed on and off in predetermined sequence, will give the effect of a rotation of the enclosure in one direction or the other and by controlling the speed of the controlling mechanism of these elements a corresponding high or low speed illusion of rotation can be effected. The annular arrangement of the light-emitting elements will, in a similar manner, create the illusion of traveling backwards or forwards while the patron 15 passes through the corresponding enclosure.
 For the purpose of controlling the flashing on or off of the light-emitting elements 23 in predetermined group sequence to create the different illusionary effects of movement, any suitable and 20 well known electric flashing device or mechanism may be employed. For example, I have shown in Figure 4, diagrammatically, a form of such device consisting of a rotor 24 included in an electric circuit 25 having switch contacts or segments 26 thereon which are disposed at different radial points about the surface of the rotor and which are adapted to successively make contact with companion switch contacts 27 suitably connected to a plurality or group of companion light-
 25 emitting tubes 23. In the example shown, these tubes have been represented as those which extend lengthwise of the enclosure and all the tubes of a given series or group are connected to the one switch contact 27 so that, say, every third 30 light-emitting tube of the whole set will light simultaneously, whereby as the rotor revolves every tube of the series connected to the first contact 27 will simultaneously light up. As the rotor continues to revolve the second series of tubes connected to the second switch contact 27 will simultaneously light up immediately after the first group goes out, and so on, this successive on and off lighting creating the illusionary effect of movement of the enclosure.
 35 To further accentuate the illusionary effects of movement created by the successive sequence lighting of the tubes 23, the platform or walkway 14 may be suspended from chains 28 or like connections and the platform imparted a slight reciprocating movement as through the medium of a reciprocating rod or pitman 29 driven from a suitable source of power, such as motor 30. By swinging or actuating the platform in this manner, the patrons as they walk over the platform will lose their sense of stability or equilibrium to a certain extent and thereby the illusionary effects created will be doubly effective.
 Instead of walking through the enclosures, cars or vehicles 31 may be used to travel over tracks 32 mounted on the platform to convey the patrons through the enclosures.
 If desired, mirrors 33, 34 may be positioned at the opposite ends of the enclosures 10 and 11, in the manner shown in Figure 1, to further 40 accentuate the illusionary effects of movement. As the patrons travel through these enclosures they see images of the light tubes 23 reflected in these mirrors thereby materially increasing the effectiveness of the illusion of movement. The mirror 34 at the front end of the enclosure 10 may be

of the phantom or transparent type, so that persons viewing this amusement apparatus from the outside may get some idea what is happening on the inside of the aligned enclosure. Mirrors 35 may be associated with the top and bottom of the upright enclosures 12 and 13 to render more effective the illusion of movement, and enlarge the patron's conception as to the size of the enclosure. 5

Referring to the modified form of the invention depicted in Figures 6-8, inclusive, 36 indicates a substantially horizontal enclosure in the form of a tube or tunnel open at its ends for the ingress and egress of patrons and having a walkway or platform 37 extending therethrough. Applied to the interior of this enclosure are a plurality of light-emitting or reflecting elements 38 which are disposed side by side from end to end of the enclosure and in this instance are preferably in the form of highly polished hoops or rings 20 secured in spaced relation to the enclosure-wall by web-like bands 39. At the exit end of the enclosure and axially aligned therewith is a disk 40 upon which light-emitting tubes 41 or the like are radially arranged and which may be 25 lighted in successive series as heretofore described to give the effect of rotation, or if desired, the same effect may be created by positively driving the disk by any suitable means, as by a motor 42 and transmission 43. By this construction, as the patrons walk through the enclosure, the effect of rotation of the enclosure is created by the revolving disk 40 as well as by the light rays reflected from the disk onto the hoops 38, the latter creating the illusion of rotation of 35 the tunnel 36.

I claim as my invention:

1. An amusement apparatus of the character described, comprising a substantially cylindrical enclosure through which patrons may pass, and a succession of parallel light-emitting elements disposed in collective predetermined fashion on the internal wall of said enclosure for intermittent lighting in predetermined sequence to produce an illusion of movement of the enclosure. 45

2. An amusement apparatus of the character described, comprising an enclosure through which patrons may pass, rows of light-emitting elements applied in substantially over-all fashion to the surrounding walls of said enclosure, and means for controlling the lighting of said elements in relatively predetermined sequence to produce an illusion of movement of the enclosure to the patrons. 50

3. An amusement apparatus for producing 55 illusionary effects of movement, comprising an enclosure having a platform therein and ingress and egress openings for the passage of patrons to and from the enclosure, a succession of light-emitting elements applied to the interior wall 60 of said enclosure from substantially end to end thereof, and means for successively controlling the lighting of said elements in predetermined sequence to give the effect of a movement of the enclosure. 65

4. An amusement apparatus of the character described, comprising a substantially cylindrical enclosure through which patrons may pass; light-emitting elements disposed in collective predetermined fashion on the internal wall of said enclosure for intermittent lighting in predetermined sequence to produce an illusion of movement of the enclosure, and reflecting means disposed adjacent an end of said enclosure and in 75

the line of vision of the patrons passing through the enclosure.

5. An amusement apparatus for producing illusory effects of movement, comprising an enclosure having a platform therein and ingress and egress openings for the passage of patrons to and from the enclosure, a succession of light-emitting elements applied to the interior wall of said enclosure from substantially end to end thereof, means for successively controlling the lighting of said elements in predetermined sequence to give the effect of a movement of the enclosure, and means for imparting a movement to said platform to transmit a sense of instability to the patrons as they pass through the enclosure.

6. An amusement apparatus for producing illusory effects of movement, comprising a pair of substantially cylindrical enclosures each having a walk-way therein and ingress and egress openings for the passage of patrons to and from the respective enclosures, and light-emitting elements disposed on the internal walls of said enclosures for intermittent, successive lighting in predetermined sequence to produce an illusion of movement of the enclosure, the light-emitting elements in one of the enclosures extending lengthwise thereof and the elements in the companion enclosure extending annularly about the same.

7. An amusement apparatus for producing illusory effects of movement, comprising a plurality of pairs of substantially cylindrical enclosures, each having a walk-way therein and ingress and egress openings for the passage of patrons to and from the respective enclosures, the enclosures of one pair being disposed in a substantially horizontal plane and the enclosures of the other pair being disposed in a substantially vertical plane, light-emitting elements applied in rows to the internal walls of said enclosures and extending substantially from end to end thereof, the light-emitting elements in one of the enclosures of each pair extending lengthwise thereof and the elements of the companion enclosures extending annularly about the same, and means for successively controlling the lighting of said elements in predetermined sequence to give the different movement effects to the enclosures, respectively.

8. An amusement apparatus for producing illusory effects of movement, comprising an enclosure having a platform therein and ingress and egress openings for the passage of patrons to and from the enclosure, a plurality of light-emitting rings applied to the internal wall of the enclosure and extending substantially from end to end thereof, and means disposed adjacent the egress end of the enclosure having light-emitting elements thereon for creating the effect of rotation, the light rays from said light-emitting elements being reflected onto said rings and creating the effect of rotation of the enclosure.

9. An amusement apparatus for producing illusory effects of movement, comprising an enclosure having a platform therein and ingress and egress openings for the passage of patrons to and from the enclosure, a plurality of highly polished rings applied to the internal wall of the

enclosure in spaced relation lengthwise thereof, a disk disposed adjacent the egress end of said enclosure in substantially axial alignment therewith, said disk having light-emitting elements thereon facing the enclosure and arranged radially on the face of the disk, and means for creating the effect of rotation of said light-emitting elements, the light rays from the latter being reflected onto said rings and simultaneously creating the effect of rotation of the enclosure.

10. In an amusement apparatus for producing an illusion of motion, an enclosure adapted to contain a patron, a plurality of sets of light-emitting elements extending about said enclosure in successive fashion, the elements of each set having therebetween elements of other sets, and means for intermittently lighting said sets of elements in sequence to produce an illusion of motion.

11. In an amusement apparatus for producing an illusion of motion, an enclosure adapted to contain a patron, said enclosure having walls with light reflecting portions, substantially uniformly-spaced light-emitting elements disposed in operative relation to said reflecting portions, and means for reflecting in advancing relation the spaced light-emitting elements upon said light reflecting portions for creating the illusion of motion of the enclosure relative to the patron.

12. In an amusement apparatus for producing an illusion of motion, an enclosure, a passenger supporting device movable in said enclosure, a plurality of sets of light-emitting elements arranged in successive fashion within said enclosure with elements of each set having therebetween elements of other sets, and means for intermittently lighting said sets in advancing order to produce the effect of motion of the enclosure relative to said device.

13. In an amusement apparatus, an enclosure adapted to contain a patron, a plurality of light-emitting elements arranged around the walls of said enclosure from end to end thereof, and means for intermittently lighting said elements in a sequence producing the effect of rings of light-emitting means constantly advancing from one end to the other end of said enclosure, thereby creating an illusion of motion of the enclosure relative to the patron.

14. In an amusement apparatus, an enclosure adapted to contain a patron, a plurality of light-emitting elements arranged around the walls of said enclosure from end to end thereof, and means for intermittently lighting said elements in a sequence producing the effect of bands of light constantly rotating around said enclosure, thereby creating an illusion of rotation of the enclosure relative to a patron therein.

15. In an illusion apparatus, a structure having a mirror on one end thereof, a transparent mirror on the opposite wall thereof, and means for lighting the interior of said structure to a greater intensity than the exterior thereof, whereby an object within said structure will appear reflected a number of times when observed from the outside of said structure through said transparent mirror.

NORMAN BARTLETT.
